US00D885137S

(12) **United States Design Patent** (10) **Patent No.:** **US D885,137 S**
(45) **Date of Patent:** **** May 26, 2020**

(54) **BEVERAGE TUMBLER**

(71) Applicant: **Vinglacé, LLC**, Houston, TX (US)
(72) Inventor: **Colton Bryan Haas**, Houston, TX (US)
(73) Assignee: **Vinglacé, LLC**, Houston, TX (US)

(**) Term: **15 Years**

(21) Appl. No.: **29/720,211**

(22) Filed: **Jan. 10, 2020**

(51) **LOC (12) Cl.** **07-01**

(52) **U.S. Cl.**

USPC **D7/531**; D7/530

(58) **Field of Classification Search**

CLAIM

The ornamental design for a beverage tumbler, as shown and described.

DESCRIPTION

FIG. 1 is a front perspective view of a beverage tumbler showing my new design;

FIG. 2 is a bottom perspective view of the beverage tumbler of FIG. 1;

FIG. 3 is a left side view of the beverage tumbler of FIG. 1;

FIG. 4 is a right side view of the beverage tumbler of FIG. 1;

FIG. 5 is a rear view of the beverage tumbler of FIG. 1;

FIG. 6 is a front view of the beverage tumbler of FIG. 1;

FIG. 7 is a top plan view of the beverage tumbler of FIG. 1;

and,

FIG. 8 is a bottom plan view of the beverage tumbler of FIG. 1.

The broken lines in the drawings depict portions of the beverage tumbler that form no part of the claimed design.

1 Claim, 7 Drawing Sheets
